UNITED STATES PATENT OFFICE.

JOHN S. STEADHAM AND WILLIAM H. STEADHAM, OF ROYSE CITY, TEXAS.

AXLE-STRAIGHTENER.

No. 805,681.

Specification of Letters Patent.

Patented Nov. 28, 1905.

Application filed August 21, 1905. Serial No. 275,088.

To all whom it may concern:

Be it known that we, JOHN S. STEADHAM and WILLIAM H. STEADHAM, citizens of the United States, residing at Royse City, in the county of Rockwall and State of Texas, have invented certain new and useful Improvements in Axle-Straighteners; and we do declare the following to be a full, clear, and exact description of the invention, such as will enable others skilled in the art to which it appertains to make and use the same.

Our invention relates to improvements in devices for straightening the metallic axles of buggies and other vehicles.

The object of the invention is to provide a simple, durable, and comparatively inexpensive device of this character by means of which an axle may be quickly and easily straightened without removing it from the vehicle and without heating it.

With the above and other objects in view the invention consists of certain novel features of construction, combination, and arrangement of parts, as will be hereinafter described and claimed.

In the accompanying drawings, Figure 1 is a side elevation of our improved axle-straightening device, showing the same in use upon the axle of a vehicle. Fig. 2 is a longitudinal sectional view, on an enlarged scale, taken on the line 2 2 in Fig. 1; and Figs. 3, 4, and 5 are transverse sectional views taken, respectively, on the lines 3 3, 4 4, and 5 5 in Fig. 1.

Referring to the drawings by numeral, 1 denotes the body of the device, which has at one end a clip 2 to engage the axle 3, at its intermediate portion a brace 4, adapted to engage the bent portion of the axle, and at its opposite end an axle-engaging clip 5 and means for adjusting said clip to bend or straighten the axle. The body 1 may be cast or formed in any suitable manner; but we preferably construct it, as shown in the drawings, from a strip of heavy sheet metal by bending the same upon itself at its center to form a tubular socket or eye 6 and then bending it adjacent to its ends to form spaced sides 7 and a reduced end 8. The end 8 and a portion 9 adjacent to the eye 6 have the two thicknesses of the strip of metal riveted or otherwise secured together, as shown at 10, and the end 8 is tapered longitudinally from about the center of the body, as shown. The clip 2 is preferably in the form of a U-shaped strip of metal through which the axle 3 and the body 1 extend. The said clip 2 may be ad-

justed longitudinally to any desired point upon the end 8, and its length may be varied by providing its ends or arms with a series of alining openings 11, through any two of which is passed a bolt 12. The latter, as clearly shown in Fig. 5 of the drawings, is engaged by the body 1. The brace 4, which is adapted to be engaged with the bent portion of the axle, as shown in Fig. 1, is adjustable longitudinally in the opened or slotted intermediate portion of the body 1, formed by the spaced sides 7. This brace 4 consists of a block having a slightly-concaved face 13 at one end to engage the axle and at its opposite end a reduced stem 14 to project through the space between the sides 7. This stem 14 is screw-threaded, and upon its outer portion is provided a washer and a clamping-nut 15.

The axle-engaging clip 5 is of U form and is pivoted by a bolt 16 to a screw 17, which extends through a spool or block 18, provided in the bent portion or eye 6 at the end of the body 1. Said screw 17 is in the form of an eyebolt, its eye 19 being disposed between the ends or arms of the clip 5 and receiving the bolt 16, which also passes through said ends or arms. A washer 20 is preferably provided upon the bolt or screw 17, and upon the outer threaded end of the latter is provided a nut 21, which has a projecting crank or handle 22.

The construction, use, and advantages of the invention will be readily understood from the foregoing description, taken in connection with the accompanying drawings. It will be seen that when the device is applied to a vehicle-axle, as shown in Fig. 1, and the nut 21 is screwed inwardly upon the screw 17 the axle will be straightened between the clips 2 5 and the brace 4.

Having thus described our invention, what we claim as new, and desire to secure by Letters Patent, is—

1. An axle-straightening device comprising a body, an adjustable axle-engaging clip at one end of said body, an adjustable brace intermediate the ends of said body, an eyebolt extending transversely through the other end of said body, a nut upon the threaded end of said bolt and an axle-engaging clip pivoted to the eye of said bolt.

2. An axle-straightening device comprising a body having an opening at one end and a longitudinally-extending slot intermediate its ends, a screw-bolt extending through the opening in said end, a nut upon the threaded

end of said bolt, an axle-engaging clip upon the opposite end of said bolt, an axle-engaging clip adjustable upon the opposite end of said body and an axle-engaging brace having a screw-threaded stem projecting through the slot in said body and a nut upon said stem, substantially as described.

3. An axle-straightening device comprising a body formed of a strip of metal bent upon itself to provide a tubular portion at one end and a slotted portion intermediate its ends, the two ends of said body being riveted together, a sleeve or spool in the tubular portion of said body, an eyebolt extending through said sleeve or spool, a nut upon the threaded end of said bolt, an axle-engaging

clip pivoted to the eye of said bolt, an axle-engaging clip adjustably mounted upon the opposite end of said body, an axle-engaging brace having a screw-threaded stem projecting through the opening in said body, and a nut upon said screw-threaded stem, substantially as described. 20

In testimony whereof we have hereunto set our hands in presence of two subscribing 25 witnesses.

JOHN S. STEADHAM.
WILLIAM H. STEADHAM.
